WILLIAM G. TUTTLE, OF GENEVA, NEW YORK.

Letters Patent No. 87,381, dated March 2, 1869.

IMPROVEMENT IN FILE FOR GAUGING THE TEETH OF CROSS-CUT SAWS.

The Schedule referred to in these Letters Patent and making part of the same.

To all whom it may concern:

Be it known that I, WILLIAM G. TUTTLE, of Geneva, in the county of Ontario, and State of New York, have invented a certain new and useful Improvement for Evening the Clearing-Teeth of Cross-Cut Saws; and I do hereby declare that the following is a full and exact description thereof, reference being had to the accompanying drawings, making part of this specification, in which—

Figure 1 is a plan of my improved instrument.

Figure 2, a similar view, looking on the opposite side.

Figure 3, a cross-section, showing the application of the instrument to the teeth of a saw, in filing.

Like letters of reference indicate corresponding parts in all the figures.

My improvement is specially applicable to that class of saws having alternate cutting and clearing-teeth, the cutting-teeth being "set" on opposite sides to cut the kerf, while the clearing-teeth stand straight forward to clear it. It is necessary, in filing, that the clearing-teeth be cut down to a shorter length than the cutting ones, and to accomplish this, my invention consists in combining, with a common file, two adjustable bars, which ride upon the points of the alternate cutting-teeth, while the file itself, which is set lower, rides upon the intermediate clearing-tooth, and cuts down its point to the right gauge.

In the drawings—

A indicates an ordinary flat-file blade, and B, its handle.

I combine with this file two flat bars C C, situated respectively on opposite sides, and parallel with the blade.

I make these bars adjustable higher or lower, relatively with the blade, by any suitable means, that rep-

resented in the drawings, being cross-pieces D D, having sockets a a, of greater depth than the blade which fits therein, and connected with the blade by screws b, b, and c, above and below.

By turning these screws correspondingly forward or back, it will be seen that the bars can be set correspondingly above the plane of the cutting-edge of the file, on either one side or the other.

The cutting down or evening of the clearing-teeth g is accomplished by setting the file-blade A below the plane of the bars C C, as shown in fig. 3, then filing said clearing-tooth down till the smooth bars strike on top of the points of the cutting-teeth, when the proper gauge will be attained. When this is accomplished, the cutting-teeth are filed in the usual way.

This is an extremely simple method of cutting down the clearing-teeth, and when the work is done, all the teeth are of an even gauge, and, therefore, the saw is in the best condition for use. When one side of the file is worn out, the adjustment can be reversed, and the opposite side used.

What I claim as my invention, and desire to secure by Letters Patent, is—

The combination of the adjustable bars C C with the file-blade A, in the manner and for the purpose specified.

In combination with the above, I also claim the cross-pieces D D, and screws b b c, in the manner and for the purpose specified.

In witness whereof, I have hereunto signed my name, in the presence of two subscribing witnesses.

W. G. TUTTLE.
